UNITED STATES PATENT OFFICE.

JAMES M. CONNER, OF GREENVILLE, NEW JERSEY.

DESIGN FOR A FONT OF LOWER-CASE TYPES.

Specification forming part of Design No. 11,159, dated April 15, 1879; application filed March 11, 1879.
[Term of patent 14 years.]

To all whom it may concern:

Be it known that, I, JAMES M. CONNER, of Greenville, Hudson county, New Jersey, have invented and produced a new and original Design for a Font of Lower-Case Printing-Types, of which the following is a specification.

The nature of my design is clearly shown in the accompanying typographic impression, to which reference is made.

It consists of an inclined Roman type free from turns in the terminations, notably of the letters d, b, i, l, m, n, and u, the terminations in these letters upon the right being brought down straight.

My present design differs from that shown in Design Patent No. 6,574, granted me April 8, 1873, in that in the present design the bottom and top lines are sharp, while in the patent of April 8, 1873, they are heavy.

Having now described my design, what I claim as new is—

The design for a font of lower-case printing-types, as shown and described.

JAMES M. CONNER.

In presence of—

Wm. C. CONNER, Jr.,
THOS. G. WILSON.
